L, L. D. VALETTON & F. E. COOK.

FRINGE.

No. 18,383.

Patented June 12, 1888.

UNITED STATES PATENT OFFICE.

GEORGE S. HENSEL, LOUIS D. VALETON, AND FRANK E. COOK, OF PHILADELPHIA, PENNSYLVANIA, ASSIGNORS TO HENSEL, COLLADAY COMPANY, OF SAME PLACE.

DESIGN FOR FRINGE.

SPECIFICATION forming part of Design No. 18,383, dated June 12, 1888.

Application filed April 28, 1888. Serial No. 272,210. Term of patent 7 years.

To all whom it may concern:

Be it known that we, GEORGE S. HENSEL, LOUIS D. VALETON, and FRANK E. COOK, citizens of the United States, residing in the city and county of Philadelphia, State of Pennsylvania, have invented and produced a new and original Design for Fringes, of which the following is a specification, reference being had to the accompanying photograph, forming part thereof.

The leading features of our design for a fringe are, first, leaf-shaped figures alternately over and below the stems of the figures, and, next, pendants, which are gathered near their tops.

15 In the photograph, A represents the head of a fringe, and B the pendants thereof. On the head are leaf-shaped figures 1 and stems 2,

which join said figures and curve upward and downward, the figures being alternately above and below said stem. The pendants B are gathered near their upper ends, forming knots 3.

We claim—

The design for a fringe herein shown and described, consisting of a head having thereon leaf-shaped figures, being alternately above and below said stems, and pendants, substantially as described.

GEO. S. HENSEL.
LOUIS D. VALETON.
FRANK E. COOK.
